FEEDING MECHANISM

Andrew K. Watt and Albert B. Hays, Lansing,
Mich., assignors to General Motors Corporation,
Detroit, Mich., a corporation of Delaware

Application September 14, 1945, Serial No. 616,330

5 Claims. (Cl. 89—33)

1.

The present invention relates to a feed mechanism particularly adapted for use with or as part of an automatic firearm of the character disclosed in Patents Numbers 1,525,065, 1,525,066 and 1,692,328, issued in the name of John M. Browning.

The feeding mechanism of a gun of the type described in the aforementioned patents heretofore did not provide satisfactory means for hand loading a belt of linked cartridges into the feed box. Such machine guns were generally loaded by manually forcing the first round of a belt of cartridges into the feed box until it tripped a pawl, commonly referred to as the carrier latch, whereupon certain spring pressed mechanism within the gun stripped the first round from the belt and drove it forward into the chamber.

While it has heretofore been suggested that a manually operable lever be connected to the feeding mechanism of such guns, such suggested levers have required extensive modification of the feed box. Furthermore, it was possible with such prior art feeding levers for an unskilled operator to manipulate the feed mechanism when the gun was not in proper condition to receive a fresh cartridge, e. g., an unfired cartridge may already be in the chamber or the lock frame would be in its battery position, thus producing a serious jam in the gun.

Accordingly, it is an object of this invention to provide a manually operable feeding lever for the above-mentioned type machine gun which may be applied to the feeding mechanism without substantial modification thereof and which will permit the feeding mechanism to be manually operated to feed successive rounds of a belt of cartridges through the gun.

A further object of this invention is to provide a safety or interlock for the feeding mechanism of a machine gun having a manually operable lever which will positively prevent manual operation of the feeding lever unless the gun mechanism is in condition to receive a cartridge, or more specifically, in accordance with this invention an interlock is provided which prevents actuation of the manual feeding lever unless the lock frame of the machine gun of the above mentioned patents is in its counter-battery position and the gun is in condition to be loaded with a fresh cartridge.

The specific nature of the invention as well as other objects and advantages thereof will clearly appear from a description of a preferred embodiment as shown in the accompanying drawings in which:

2.

Fig. 1 is a longitudinal sectional view of the breech and feeding mechanism of an automatic cannon of the type more particularly illustrated and described in the aforementioned patents to Browning. The elements in Fig. 1 are shown in their battery positions;

Fig. 2 is a partial view similar to Fig. 1 but showing the elements in their partial counter-recoil position;

Fig. 3 is a perspective view of the feed box of a firearm of Fig. 1 showing the interlock element in its operative position;

Fig. 4 is a perspective view of the rear portion of the feed box of Fig. 3 showing the interlock element in its inoperative position and the manually operable lever in a retracted position;

Fig. 5 is an enlarged sectional view of the interlocking element;

Fig. 6 is a top elevational view of a preferred form of the operating lever; and

Fig. 7 is a cross-sectional view taken along line 7—7 in Fig. 6.

The drawings fully show the improvements to the feeding mechanism of this type of machine gun to which the invention particularly relates and they also show certain other portions of the gun with which the improvements directly cooperate. For details of the gun which are not herein fully described reference may be had to the aforementioned Browning patents.

The gun as shown consists of a frame or breech casing which is rectangular in form and adapted to contain the breech and firing mechanism. The casing comprises two spaced vertical side plates 2 and a top plate 3. Projecting forwardly from the casing is a barrel or tube 4, the chamber end of which is rigidly secured to a barrel extension 5. The barrel and barrel extension move rearwardly upon recoil within the casing and are suitably guided by the side plates 2. Also longitudinally movable within the casing is a lock frame 6.

In the normal functioning of the gun, as fully described in the aforesaid patents, the barrel, barrel extension and lock frame initially move rearward in unison upon recoil. The barrel and barrel extension immediately return forwardly to their battery position shown in Fig. 1 but the lock frame is held in a recoiled position by means of a sear 7 commonly referred to as the carrier dog which engages a notch 6a in the lock frame. By means of suitable reaction springs (not shown), the lock frame is spring loaded for forward movement when released by the carrier dog 7.

Carried by the casing at the top thereof is

a feed box 8 which is preferably rectangular in form having vertical side walls 9 and 10 and front and rear walls 11 and 12. The entire feeding mechanism is housed within feed box 8. The invention is illustrated in connection with a right hand feed gun, the feed box 8 being provided on its right hand side with a feed slot 13 (Fig. 3) of suitable shape to permit a linked belt of cartridges to pass therethrough and a pressed metal feed chute 14 is provided aligning therewith through which cartridges 15 secured together in conventional manner by belt links 16 pass into the feeding mechanism. The left side of feed box 8 as viewed in Fig. 3 is provided with a discharge slot 17 through which the links 16 are discharged.

A pair of spaced guide members 19 and 20 are provided extending across the top of feed box 8 on which a feed slide 21 is mounted for reciprocal movement as is more fully described in the aforementioned patents. A conventional pawl 70 (Fig. 3) is provided on the underside of feed slide 21 to engage successive links of the belt of cartridges to advance such belt into the feed box 8 with each reciprocation of feed slide 21.

A feed slide return lever 22 is pivotally mounted in the forward end of feed box 8 and engages feed slide 21 by means of a pin 25 cooperating in a slot 25a. A spring pressed plunger 23 (Fig. 3) imparts a bias to feed slide return lever 22 which in turn biases the feed slide 21 to its extreme right hand position as viewed in Fig. 3.

Feeding movement is imparted to feed slide 21 after the firing of each cartridge by a conventional linkage which is actuated by the counter recoil movement of the barrel extension 5. For the purposes of this invention, it is not necessary to describe all portions of this linkage completely but it will be sufficient to point out that the feed slide 21 is immediately operated by a feed slide lever 50 (Fig. 3). Feed slide lever 50 is pivotally mounted in the feed box 8 on a pin 51 and has one end pivotally secured to the feed slide 21 by a pin and slot connection 24 and its other end pivotally secured to the end of one arm 26a of a right angle feed crank 26 through a pin and slot connection 71. The feed crank 26 is pivotally mounted at its vertex by means of a depending vertical pin 27 which is supported for movement about a horizontal axis in a suitable bearing (not shown) provided in the feed box 8. The other arm 26b of feed crank 26 is operated by a feed lever 28 mounted in casing 8 and pivoted forwardly during counter-recoil of barrel extension 5 by a stud 29 thereon. Feed lever 28 engages arm 26b at 30 as shown in Figs. 3 and 4 and thereby transmits motion to feed crank 26.

The structure thus far described has been substantially similar to that set forth in the aforementioned patents. In accordance with this invention a manual operating member or loading lever 31 is provided, having an integral plate-like body portion 32 which is mounted coaxially and in surrounding relationship with respect to pin 27 of feed crank 26. Loading lever 31 has an integrally formed handle portion 33 which projects out of the right hand side of feed box 8 as viewed in Fig. 3 through a suitable slot 34. The plate-like body portion 32 of loading lever 31 underlies feed crank 26. A pawl-like projection 36 (Fig. 6) is provided on body portion 32 in position to engage a depending stud 37 in feed crank 26 so that rotation of loading lever 31 by pulling handle 33 rearwardly will in turn impart a rotational movement to feed crank 26 to actuate feed slide 21 in a direction to feed a round into the gun.

Preferably an extension spring 39 is mounted between a depending stud 52 on the bottom of body portion 32 of loading lever 31 and the wall of feed box 8 and operates to return loading lever 31 to its inoperative position. The remainder of the feed mechanism is returned to its ready-to-feed position by the spring biased feed slide return lever 22. Thus a manually operated actuating lever for the feeding mechanism of a machine gun of the type disclosed in the aforementioned patents is provided without substantial modification of the prior art structure.

In accordance with this invention an interlock 40 is provided to prevent manual operation of loading lever 31 except when the lock frame 6 is in its loading position heretofore described wherein the carrier dog 7 engages in notch 6a in the lock frame 6. The interlock 40 comprises a plate or stop portion 42 which is threadably secured to a depending plunger portion 41. The plunger portion 41 is slidably mounted in a hollow vertical housing 43 which is formed in the rear wall 12 of the feed box 8. A spring 44 is disposed between plunger portion 41 and the interior wall of housing 43 and operates between an internal shoulder 43a of housing 43 and an enlarged head portion 45 on plunger portion 41, thus normally biasing interlock 40 to a down position. In such down position, the plate portion 42 of interlock 40 is disposed as shown in Fig. 3, immediately in the path of a projection 38 integrally formed on loading lever 31, thus preventing manual operation of the loading lever. Also, in such down position, the end 53 of the interlock plunger 41 extends into the path of a portion of the carrier dog 7.

The vertical position of the plate 42 of interlock 40 is thus determined by the pivotal position of the carrier dog 7 and this position is in turn determined by the position of the lock frame 6. The carrier dog thus functions as an actuator for the interlock 40. As is more fully described in the aforementioned patents, carrier dog 7 is pivotally mounted on a carrier 46 which is in turn pivotally mounted in feed box 8 for movement about a horizontal axis. In the battery position of lock frame 6 as illustrated in Fig. 1, carrier dog 7 projects downwardly into the path of recoil movement of the lock frame under the force imparted by a spring pressed plunger 47 which seats in a hole 48 in carrier 46. As the lock frame 6 moves rearwardly upon recoil, the carrier dog 7 is rotated upwardly about its mounting pin and upon the counter-recoil of frame 6 is engaged therewith by means of notch 62. This upward movement in turn is imparted to the interlock 40. The plate 42 of interlock 40 is thus raised vertically to clear the projection 38 of loading lever 31. Hence, loading lever 31 may be manually operated to feed a cartridge into the gun.

Carrier dog 7 is released from the notch 6a in lock frame 6, permitting the lock frame to drive forward, by mechanism responsive to feeding movement of the feeding mechanism. However, the mechanism by which this is accomplished is completely described in the aforementioned patents and forms no part of this invention.

It is therefore apparent that improvements in accordance with this invention provide a simple yet effective manual operating lever for the feed mechanism of a machine gun and in addition prevents actuation of such manual lever unless

the gun mechanism is in proper condition to have a cartridge loaded therein.

We claim:

1. In a machine gun having a recoiling member and a feed slide mounted on the gun for reciprocable movement, the improvement comprising, in combination, a crank member pivotally mounted in the gun and arranged to transmit movement of the recoiling member to the feed slide, an operating member pivotally mounted adjacent to and coaxial with said crank member, a handle portion on said operating member projecting out of the gun, and a projection on said operating member directly engageable with said crank member whereby manual operation of said handle portion rotates said crank member in a cartridge feeding direction.

2. In a machine gun having a recoiling member and a feed slide mounted on the gun for reciprocating movement, the improvement comprising, in combination, an operating member pivotally mounted on the gun, a handle portion on said operating member projecting out of the gun, means interconnecting said operating member with said feed slide whereby pivoting of said handle portion actuates said feed slide, a stop member normally disposed in the path of movement of said operating member to prevent movement thereof, and means responsive to the position of said recoiling member for moving said stop member out of the path of said operating member.

3. In a machine gun having a recoiling member and a feed slide mounted on the gun for reciprocable movement, the improvement comprising, in combination, a crank member pivotally mounted on the gun and arranged to reciprocate the feed slide, an operating member coaxially pivotally mounted relative to said crank member, a handle portion on said operating member projecting out of the gun, a projection on said operating member engageable with said crank member to rotate said crank member in a cartridge feeding direction by manual operation of said handle portion, whereby pivoting of said handle portion actuates said feed slide, a stop member normally disposed in the path of movement of said operating member to prevent movement thereof, and means responsive to the position of said recoiling member for moving said stop member out of the path of said operating member.

4. In a machine gun having a recoiling member and a feed slide mounted on the gun for reciprocating movement, the improvement comprising, in combination, an operating member pivotally mounted on the gun, a handle portion on said operating member projecting out of the gun, means interconnecting said operating member with said feed slide whereby pivoting of said handle portion actuates said feed slide, a stop member movably mounted on the gun adjacent said operating member, resilient means biasing said stop member into the path of movement of said operating member to prevent movement thereof, and an actuator pivotally mounted on the gun and arranged to be moved by the recoiling member, said actuator being connected to said stop member and constructed and arranged to move said stop member out of the path of said operating member in response to the position of the recoiling member.

5. In a machine gun having a recoiling member, a sear pivotable into engagement therewith to secure the recoiling member in a recoiled position, and a feed slide mounted on the gun for reciprocating movement, the improvement comprising, in combination, an operating member pivotally mounted on the gun, a handle portion on said operating member projecting out of the gun, means interconnecting said operating member with said feed slide whereby pivoting of said handle portion actuates said feed slide, a spring pressed plunger movably mounted in the gun, said plunger being engageable with and movable by said sear, a stop member secured to said plunger and arranged to lie in the path of movement of said operating member when the sear is engaged with the recoiling member and to be moved out of the path of movement of said operating member when said sear moves out of engagement with the recoiling member.

ANDREW K. WATT.
